NORMAN R. SMITH AND PAUL A. TALBOT, OF SEATTLE, WASHINGTON,
ASSIGNORS TO THE SEATTLE ROTARY ENGINE COMPANY, OF SEATTLE,
WASHINGTON, A CORPORATION OF WASHINGTON.

VALVE-OPERATING MEANS FOR ROTARY ENGINES.

No. 833,848.

Specification of Letters Patent.

Patented Oct. 16, 1906.

Application filed December 4, 1905. Serial No. 290,258.

To all whom it may concern:

- Be it known that we, NORMAN R. SMITH and PAUL A. TALBOT, citizens of the United States, and residents of the city of Seattle, in the county of King and State of Washington, have invented certain new and useful Improvements in Valve-Operating Means for Rotary Engines, of which the following is a specification.
- Our invention relates to an improvement in the valve and valve-operating means of the rotary engine shown in the patent issued to Norman R. Smith, October 24, 1905, No. 802,828.
- The object of our invention is to provide a positive and reliable means for shifting the valve to reverse the engine, such means to be operative by hand through positive mechanism.
- Our object is, further, to simplify and improve such mechanisms.

Our invention comprises the novel parts and combinations of parts hereinafter particularly pointed out in the claims.

- The drawings show our invention embodied in the form now preferred by us.
- Figure 1 shows the rotary head, shaft, and valve-actuating mechanism, parts being in section. Fig. 2 is a section through the rotary head, taken in a plane at right angles to the shaft. Fig. 3 is a face view of the head, showing a valve-seat, that portion of the head covering the valve being removed. Fig. 4 is a face view of one-half the valve.

- Our invention is applied to a form of engine which, except in its valve and valve-operating mechanism, is the same as is shown in the patent issued October 24, 1905, to Norman R. Smith, No. 802,828. We have therefore not shown and will not describe the general features of construction and operation of the engine. We will only say that this engine has a circular cylinder or casing, a rotary head of an outline resembling an ellipse, and abutments which are segments of an annulus and are connected in pairs swinging on pivots placed outside the cylinder and actuated by the non-circular outline of the rotary head.
- The steam is admitted through the rotary head from ports in the casing-heads. Ports 1, which pass entirely through the rotary head, register with the ports in the casing-

head as the rotary head turns. The periodicity and duration of admission of steam is 55 determined by the relative size and location of these ports.

The course of the steam after being admitted to the ports 1 is determined by the valves 4, two of which are shown, one for 60 each lobe of the rotary head. These valves are seated in channels formed in the body of the head and lie in planes which are parallel with the shaft or axis of rotation. The steam-passages 1 communicate with the 65 valve-seat by two sets of ports 10. The valves 4 have a single corresponding port 40, which in one position of the valves register with one of the ports 10 and in the other position of the valve register with the other 70 port 10. In this manner the admission of steam to either one of the ultimate discharge-ports 2 or 3 is controlled. In the position shown in Fig. 2 steam is being admitted through ports 3 and the other similar ports 2 75 are being used as exhaust-ports. Shifting the valve would reverse this condition. The exhaust from without the rotary head is through the ports 43 into and through the interior chamber 44. Half of the ports 43 are 80 closed in one position of the valves and the other half are closed in the other position of the valves. The ends of the valves are shaped to conform to the outline of the rotary head, so as to maintain a smooth and 85 steam-tight surface for the abutments to contact with. These ports 2 or 3, as the case may be, which are not in use for the admission of steam, are connected with the central 90 exhaust-chamber 44 by ports 20 or 30 in the rotary head and ports 41 in the valve 4.

Each valve 4 has a recess 8 in one face, which is designed to receive a pin 60, carried by a crank-arm 6. A rock-shaft 5 is journaled in the rotary head and extends between 95 the two valves 4. At each end this carries a crank-arm 6, having a crank-pin 60. The arms at opposite ends of the shaft extend oppositely, so as to shift their respective valves oppositely. The rock-shaft has a central 100 operating-arm 7, which extends through a slot 14 in the shaft 11 and enters a slot 70 in the valve-shifting shaft 71, which lies in a central bore in the shaft 11. This shaft 71 extends beyond the end of the shaft 11 and 105 is provided with means by which it may be

engaged to reciprocate it. The means shown consist of a grooved hub or ring 12, keyed to the shaft, and a trunnion-ring 13 engaging therewith and adapted to be connected with a lever.

5 The crank-pins 60 have their outer surfaces segments of a circle concentric with the rock-shaft, and the slots 8 have a portion of their slides segments of circles of the same 10 radius and so disposed that in the extreme positions of the valves they alternately come concentric with the rock-shaft. In these positions the outer surfaces 61 of the crank-pins coincide in curvature and position with one 15 or the other of the curved surfaces 80 of the slots 8 in the valve.

The side surfaces of the pins 60 engage the straight parts of the slots 8 to throw the valve. At the time when the valve reaches 20 its proper position the corner of the pin reaches the corner of the side surfaces of the slot 8 in the valve, and further movement of the crank-arm throws the pin past this corner, but without moving the valve, as the 25 correspondingly-curved surfaces of the pin and slot simply slide upon each other, both being of the same curvature and concentric. This obviates the necessity for an exact travel of the crank-arms and also provides a 30 positive lock to prevent the valve moving backward until the rock-shaft is turned. Strain exerted upon the exposed end of the valve by the working steam-pressure is resisted by the crank-pin without any tendency 35 to turn the rock-shaft. The clutch device by which the valve-shifting shaft 7 is operated is therefore relieved of all strain except at the time of shifting the valve and will consequently wear very little.

40 By the above means we provide a positive hand-operated valve-shifting mechanism and can therefore be certain that the valve may be shifted whenever desired. There is therefore no more uncertainty about the operation 45 of this valve-shifting mechanism than there is about that of any ordinary engine.

Having thus described our invention, what we claim, and desire to secure by Letters Patent, is—

50 1. In a rotary engine, in combination, a rotary head having supply and exhaust ports therein, a valve in said head located eccentric to its axis and controlling said ports, and positive means for shifting said valve from without the cylinder.

55 2. In a rotary engine, in combination, a rotary head having supply and exhaust ports therein, a valve in said head located eccentric to its axis and controlling said ports, a 60 valve-shifting shaft at the axis of said rotary head and connections from said shaft to the valve to shift it.

65 3. In a rotary engine in combination, a rotary head having steam-ports therein, a 65 valve in said head controlling said ports, a

valve-shifting shaft mounted to reciprocate in the axis of the rotary head, and a lever mounted in the rotary head and connecting the valve-shifting shaft and the valve.

4. In a rotary engine, in combination, a rotary head having steam-ports therein, a valve controlling said ports and mounted to reciprocate in a plane parallel with the axis of rotation, a rock-shaft journaled in said rotary head and having one arm engaging the 70 valve and another arm extending to the center of the rotary head, and a valve-shifting shaft mounted to reciprocate in the axis of the 75 rotary head and engaging the arm of the rock-shaft.

5. In a rotary engine, in combination, a rotary head and its shaft, said head having steam-ports, a valve controlling said ports, a lever within said head engaging the valve and extending to the shaft center, said shaft having 80 a slot to receive said lever and to permit its movement, a shifting-shaft mounted to be reciprocated in the axis of the shaft carrying the rotary head, and connected with said lever, and a shifting member having relatively rotative connection with the shifting-shaft outside the engine-cylinder.

85 6. In a rotary engine, in combination, a rotary head having supply and exhaust ports therein, and a valve in the head controlling 90 said ports, positive means for shifting said valve from without the engine-cylinder, and means for locking said valve in its normal positions.

95 7. In a rotary engine, in combination, a rotary head having supply and exhaust ports therein, a valve within said head controlling 100 its ports, positive means for shifting said valve from without the engine-cylinder, and means comprising relatively non-rotative 105 members for locking said valve in its normal positions.

8. In a rotary engine, in combination, a rotary head having supply and exhaust ports therein, a valve within said head controlling 110 said ports, means for positively shifting said valve from without the engine-cylinder comprising therein a thrust-bearing, and means between said thrust-bearing and the valve 115 for locking the valve in its normal positions.

9. In a rotary engine, in combination, a rotary head having steam-ports therein, a valve mounted in said rotary head and controlling the steam-ports, a lever pivoted in said rotary head and engaging the valve to 120 shift it, said lever and valve having circular segmental surfaces which come into concentric engagement in the normal positions of the valve to lock it in place.

10. In a rotary engine, in combination, a 125 valve and a lever engaging said valve to shift it, said lever and valve having circular segments which come into concentric engagement to lock the valve in its normal positions.

11. In a rotary engine, in combination, a rotary head, having steam-ports therein, a valve in said head controlling said ports, a lever in said head engaging the valve to shift it, said lever and valve having circular segments which come into concentric engagement to lock the valve in its normal positions, and means for operating said lever from without the engine-cylinder. 5
12. In a rotary engine, in combination, a rotary head, having opposite lobes, a valve mounted to reciprocate in each lobe, a rock-shaft journaled in the rotary head and having crank-arms engaging both valves, and an actuating-arm extending to the axis of the rotary head, and a valve-shifting shaft lying in the said axis and extending from said actuating-arm, to the outside. 10
13. In a rotary engine, in combination, a lobed rotary head having supply and exhaust ports adapted for reverse rotation, a valve controlling the ports for each lobe, a rock-shaft mounted within the head and having arms engaging each its respective valve, and an actuating-arm extending to the axis of rotation, a valve-shifting shaft lying in said axis and thrust-bearing connection to reciprocate said shaft. 15
14. A lobed rotary head for rotary engines, having a valve-seat extending transversely to each lobe and extending to the periphery at 20
- each side of the lobe, said openings being adapted to act as a port, and a valve mounted to reciprocate in said seat-opening and by its ends to close the same. 25
15. A rotary head for rotary engines, having lobes and a valve-seat extending transversely of each lobe and extending to the periphery at each side, said peripheral openings being adapted to act as exhaust-ports, a valve in each of said seats having ends adapted to close said peripheral openings and means for shifting said valves across the lobes. 30
16. A rotary head for rotary engine, having valve-seats extending across the same from one periphery to the other, a valve mounted in said seat and having ends adapted when shifted to its extreme throw to close said openings and having end surfaces which continue the curve of the rotary head across the said openings. 35
